UNITED STATES PATENT OFFICE.

ERNON V. OLIVER, OF PORTLAND, OREGON, ASSIGNOR OF FIVE-TWELFTHS TO HANS PETERSON, OF PORTLAND, OREGON.

BOX-NAILING FORM.

1,416,280.

Specification of Letters Patent. Patented May 16, 1922.

Application filed January 4, 1921. Serial No. 434,880.

To all whom it may concern:

Be it known that I, ERNON V. OLIVER, a citizen of the United States, residing at Portland, in the county of Multnomah and 5 State of Oregon, have invented certain new and useful Improvements in Box-Nailing Forms, of which the following is a specification.

This invention relates to apparatus for 10 supporting the ends and intermediate partitions of boxes while the sides and bottom are nailed thereto and one object of the invention is to provide an apparatus which is strong and durable and will firmly support 15 the ends and the partition until the box is completed. A further object of the invention is to provide means which will firmly hold the partition and box ends while permitting ready shifting of the same to permit 20 the attachment thereto of the successive sides. A further object of the invention is to provide an apparatus for the stated purpose which may be quickly and easily adjusted so as to be used in connection with 25 boxes of any dimensions and also to permit such adjustment of the parts as will accommodate box ends or partitions of any thickness. Other incidental objects of the invention will appear in the course of the following 30 description and the invention resides in certain novel features which will be particularly pointed out in the appended claims.

One embodiment of the invention is illustrated in the accompanying drawings, in 35 which—

Figure 1 is a perspective view of an apparatus having my improvements incorporated therein;

Fig. 2 is a transverse section of the same;

40 Fig. 3 is a detail section through a portion of the box end supporting clamp;

Fig. 4 is a detail perspective view of a portion of the base strip upon which the box end rests while the side or bottom is being 45 nailed thereto;

Fig. 5 is an enlarged perspective view showing the manner in which the box ends and the partition are held in an upright position by the use of the apparatus while a 50 side is being attached;

Fig. 6 is a detail perspective view of a tool holder which may be mounted upon the machine;

55 Fig. 7 is an enlarged transverse section of the device shown in Fig. 4;

Fig. 8 is a detail perspective view of a gripping washer employed in connection with the box end-engaging clamp;

Fig. 9 is a detail.

In carrying out my invention, I employ 60 a supporting frame which may be of any convenient form but is preferably constructed of metal angle bars 1, constituting posts, connected at their upper ends by bracing bars 2, as clearly shown in Fig. 1. The posts or 65 corner bars 1 are closed at their ends by webs 3 so as to attain the greatest possible rigidity and permit the corner joints to be thoroughly braced. It is also intended to weld the meeting parts together so that the 70 greatest possible strength will be attained. The posts are provided with openings 4 through their branches or flanges, the series of openings extending from end to end of each flange and thereby permitting the attachment of the supported parts at any desired height whereby to accommodate the apparatus to the convenience of the workman. The corner posts 1 may rest at their lower ends directly upon the ground or upon 80 the floor of a workroom, but I prefer to employ supplemental posts or feet 5 which are similar in construction to the corner posts 1 and are adjustably secured to the lower ends of the posts by bolts 6 inserted 85 through registering openings in the flanges of the posts 1 and the supplemental posts or feet 5, as will be readily understood. To further brace the frame, a longitudinal bar 7 is secured at its ends to the cross bars 2, 90 at the centers thereof, so that lateral spreading of the end supporting frames will be prevented.

A bench 8 is supported by the end frames and this bench is also preferably constructed 95 of angle bars, the front and rear angle bars 9 being secured to the front and rear flanges of the respectively adjacent corner posts and being connected by end bars 10 which further brace the structure and prevent spreading of the parts. The bars 9 and 10 will be preferably welded together at their junctions and the bench frame, consisting of the said bars, will be secured to the posts by bolts 11 inserted through registering openings in the flanges of the posts and the vertical flanges of the bench frame. It will thus be readily seen that the bench may be supported upon the posts at any desired height and the workman, therefore, per- 100 105 110

mitted to set the apparatus so as to suit his convenience. Intermediate bars 12 extend between the end bars 10 of the bench frame and these intermediate bars are also of angle 5 iron and have their vertical flanges slit at their ends so that the ends of their horizontal flanges form tongues 13 resting upon the horizontal flanges of the end bars and thereby supported. The vertical flanges of the 10 intermediate bars 12 have their ends, furthermore, bent against and welded to the end bars 10 so that a rigid structure will be produced; they serve to reinforce the bench frame and, together with the frame bars 9 and 15 10, constitute a substantial unitary bench which will withstand rough usage and prevent collapse under the shock applied thereto during the nailing operations. To further brace the bench, brace bars 14 are 20 secured to the side and end bars of the bench frame, preferably by welding, and have their lower ends secured by the same bolts 6 which connect the corner posts and the feet or supplemental posts 5. The bars 9 and 12 are 25 provided with openings 15 through their horizontal flanges, the series of openings extending practically from end to end of the several bars, and rests 16 are disposed across and adjustably secured to the said 30 bars by bolts inserted through openings in the rests and through registering openings 15, as will be readily understood. Obviously, the rests are adjustable from end to end of the bars 9 and 12 so that they may be set at 35 any point along the same according to the length of the box to be made and it is also obvious that if the box is not to have a central partition one of the rests may be removed or shifted close to the end of the 40 bench where it will be out of the way and the remaining two rests brought as closely together as may be necessary to correspond to the distance required between the ends of the box. The upper ends of the openings 17 45 through the rests are so formed that the heads of the securing bolts may be flush with the upper surface of the respective rests and, consequently, be out of the way of the box ends when the apparatus is in use. The 50 rests are also constructed with transverse recesses or grooves 18 and slots 19 opening through the bottoms of said grooves. Clamping plates 20 may be fitted in the respective grooves 18 and said clamping plates have 55 upstanding lugs 21 at their inner ends, bolts 22 being carried by the plates and depending through the slot 19 to be secured at any desired point of the said slot by nuts 23 and washers 24 fitted upon the lower ends of the 60 bolts, as will be readily understood. When the box end is a built-up member and not constructed of a single piece of lumber, as is 65 frequently the case, the pieces which are to be joined to make the box end are laid upon the rests and the clamping plates are

adjusted so that the lugs 21 will bear against the opposite edges of the said pieces and hold them in proper position while cross pieces are nailed thereto but when the box ends are sawed complete from a piece of 70 lumber, these clamping plates are removed or reversed so that the lugs 21 will project downwardly and bear against the sides of the rests as, otherwise, they will interfere with the turning of the box to facilitate the 75 nailing of the successive sides. It will also be understood, of course, that after the fabricated box ends have been completed the lugs will be removed to permit the box ends to be properly supported and shifted as the 80 nailing operation progresses. It will also be understood that when box-ends are being fabricated, the box-supporting clamps and the parts cooperating therewith are removed, or else adjusted to the extreme rear of the 85 machine so as to be out of the way.

Secured to the outer sides of the posts 1, above the bench, are the bars 25 and 26 which are bolted to the posts and are provided with openings 27 therethrough, as 90 clearly shown. These bars 25 and 26 further brace the end frames and also form the foundation supports for the box end-engaging clamps. The bolts which secure the upper bars 26 to the rear corner posts also 95 support the supplemental or extension bars 126 which are provided with a longitudinal series of openings 127 to permit the fastening bolts or other members engaged therewith to be adjusted in order to vary the effective length of the bars as may be desired. At their front ends, the extension bars are 100 provided with hooks or lips 128 extending laterally from their lower edges to engage under the lower edges of the bars 26 and thereby restrain the extension bars from 105 dropping under strain applied to their rear ends. In the rearmost openings 127, I engage the lower ends of small standards 28, the said lower ends of the standards being 110 threaded to receive nuts 29 which may be turned home against the adjacent bar 126 to secure the standard in an upright position. Against the standards 28, I place a board or strip 30 which will rest on its edge upon 115 the bars 126 and bear against the said standards so as to constitute a back rail or rest, as most clearly shown in Fig. 2. Upon the bars 126, in advance of the said rail 30 and bearing against the front side of said rail 120 at the lower edge thereof and extending to the posts 1, I place boards or plates 31 thereby producing a shelf or support for box ends and sides so that the workman will have a 125 constant supply within ready reach and will not be delayed in his work by waiting for material.

Secured in and extending between the corresponding bars 25 and 26 are rods 32 and upon the said rods 32 are adjustably mount- 130

ed posts 33 which carry the box end-engaging clamps. These posts 33 consist each of an upright bar or block 34, and slidably mounted upon rods 32 to be moved to or from the bars 34 are liners 35 of similar form but of less thickness. By shifting all the adjacent liners away from a block or bar 34 or bringing one or more of the liners against the said block or bar, the thickness of the post may be readily made equal to the thickness of the box end which is to be supported, and corresponding openings 36 are formed through the bars or blocks 34 and the liners 35 so that the bolts or securing devices of the box end-engaging clamps may be readily set at the desired height. In Figs. 1 and 3, the liners are shown away from the bars and in Fig. 5 a single liner is shown against the side of the bar. The bars 34 and the liners are provided adjacent their upper and lower ends with openings 37 through which the bars or rods 32 pass so that the posts will be supported in an upright position and may be readily shifted along the rods 32 to accommodate boxes of different lengths. After the posts have been properly spaced upon the rods 32, set screws 38, carried by the posts, are turned home against the rods so as to secure the posts in their set positions. Obviously, the upper and lower rods 32 are in the same vertical plane and the adjustment of the rests 16 is the same as the adjustment of the posts 33. Carried by each post 33 is a box end-engaging clamp consisting of similar plates 39 and 40 disposed against the opposite sides of the respective posts and projecting forwardly therefrom in parallelism. These plates 39 and 40 are provided with longitudinal slots 41 through which the retaining bolts 42 are passed, the said bolts obviously passing through openings 36 in the posts alined with the said slots. The plates 39 and 40 are provided in their outer faces above and below the slot 41 with sockets 43 and a gripping washer 44 is disposed against each plate so as to bridge the slot 41 and the said sockets, as shown most clearly in Fig. 3. The said gripping washer is provided on one face with teats or lugs 46 adapted to engage the sockets 43 so that rotation of the clamping plate while the machine is in use will be avoided. The gripping washer is also provided with openings 47 therethrough adjacent its ends and between the said teats, the bolts 42 passing through the said openings 47 and through the slots 41 of the clamping plates and the alined openings 36 of the posts. Between one washer 44 and the heads 48 of the bolts passing therethrough, I coil springs 49 which serve to yieldably hold the clamping plate 39 against the side of the post. At the opposite side of the post, a washer 51 is mounted upon the bolt 42 and a wing nut 52 is fitted upon the bolt against the said washer, a spring 53 being coiled around the bolt between the washers 44 and 51, as clearly shown in Fig. 3. It will be readily understood that by turning the nuts 52 home, the springs 49 and 53 will be placed under tension so that the plates 39 and 40 will be held closely against the posts 34 and also against the opposite sides of a box end or partition inserted between the plates. The ends of the clamping plates are slightly diverged or curved outwardly, as indicated at 54, so that the box end or the partition may be easily inserted therebetween. It is obvious that the clamping plates may be set at any desired height of the posts 33 and the bolts 42 inserted after the plates have been set vertically. By slightly relieving the tension of the springs 49 and 53, the plates may also be shifted forwardly or rearwardly without disturbing their vertical adjustment so that the clamp may be set to accommodate box ends or partitions of any dimensions.

In one of the openings through the rear bar 9, I insert the lower end of a post 60 and upon the said post above and below the bar I mount clamping nuts 61 which are adapted to be turned home against the bar and thereby secure the post rigidly in position. The upper end of the post 60 is extended laterally, as at 62, and then again carried upwardly, as at 63, a brace 64 being extended between the base of the vertical member 63 and the main post 60, as clearly shown. Over the upper end of the member 63, I fit an inverted cup or thimble 65 and upon the upper end of the said thimble I secure or form a plate 66 which is illustrated as being star-shaped and having a plurality of radial arms 67 in the outer ends of which are openings 68. Bolts may be inserted through the openings 68 to secure to the plate 66 any one of the nail-strippers in common use by box-makers and the thimble 65 may be rotated about the member 63 so that the stripper may be readily brought to the position most desirable to the workman.

It is thought the use of the apparatus will be readily understood. The clamping plates 39 and 40 having been adjusted to the dimensions of the box to be finished, box ends, indicated at 70 and 71, and an intermediate partition, indicated at 72, if the same is to be used, are placed on edge upon the rests 16 and pushed in between the plates 39 and 40 so as to be frictionally held by the same. One side of the box, indicated at 73, is then placed upon the upper edges of the box ends and the partition and nails driven through the side into the partition and the ends in the usual manner. After the side has been thus secured in place, it is lifted slightly and the box ends and partition thus raised from the respective rests, after which the box side with the ends and partition attached thereto

are rotated so that the nailed side will be at the front of the apparatus, after which the partly finished box is lowered and pushed rearwardly so that it will be supported by the rests 16 and the box ends and partition firmly held by the box end-engaging clamps. The bottom is then nailed in place and the described operation repeated in order to bring the third side of the box uppermost, 10 the first completed side then being at the bottom of the box and the box bottom being at the front of the apparatus. The partly finished box may then be withdrawn from the clamps and put aside and another 15 box nailed. The top of the box is not placed thereon until after the box is filled so that after the bottom and two sides have been secured in place the work in which my apparatus is used is finished.

20 It will be readily seen that I have produced a very strong and durable apparatus by the use of which the production of the boxes will be greatly facilitated. The box ends and the partition, when the same is 25 used, will be firmly supported in an upright position so that the workman is not called upon to hold either box end or the partition while nailing a side or a bottom thereon and the frictional engagement of the clamping 30 members upon the box ends and the partition yields sufficiently to permit the box to be readily turned as the workman is ready to nail an additional side, while at the same time collapse of the structure is prevented.

35 Should it happen that a box end inserted in one of the clamps is somewhat thinner than the gage adopted for the clamp, a block of any convenient material or form may be inserted between the rear ends of the clamping 40 plates so that the plates will be caused to rock laterally relative to the posts upon which they are mounted and the front ends of the plates thereby caused to firmly grip the box end. It will be noted, more 45 particularly upon reference to Fig. 1, that the rods 32 are threaded at one end and secured in the end frames by nuts mounted on the rods and turned home against the bars 25 and 26. I am thus enabled to readily withdraw the said rods if the device is to be 50 out of use for any considerable period and the space occupied by the apparatus when it is set up may be utilized for other purposes, it being noted that the bench is 55 secured to the end frames by bolts and the material-supporting shelf is also secured to the end frames by bolts so that the parts may be very easily disassembled and stored in a small space.

60 Having thus described the invention, what is claimed as new is:

1. In an apparatus for the purpose set forth, the combination of end frames, a bench supported by and between said end 65 frames, supporting members extending be-

tween the end frames, posts mounted on said supporting members above the bench, and box-end-engaging clamp carried by said posts.

2. In an apparatus for the purpose set forth, the combination of a bench, posts supported above the bench, and box-end-engaging members carried by said posts and adjustable vertically and horizontally thereon.

3. In an apparatus for the purpose set forth, the combination of a bench, posts supported above the bench, clamping plates disposed against the opposite sides of the posts and projecting forwardly and rearwardly therefrom, and means supported by the posts 80 for yieldably holding the clamping plates thereto and permitting horizontal adjustment of the plates forwardly and rearwardly relative to the post.

4. In an apparatus for the purpose set forth, the combination of a bench, posts supported above the bench, clamping plates arranged against the opposite sides of the posts and projecting forwardly therefrom and provided with longitudinal slots, securing 90 bolts inserted through the said slots of the clamping plates and through the posts, and springs coiled around the bolts and acting upon the outer sides of the clamping plates to hold the plates to the posts and permit 95 adjustment of the same horizontally across the posts.

5. In an apparatus for the purpose set forth, the combination of a bench, posts supported above the bench, clamping plates disposed against the opposite sides of the posts and provided with longitudinal slots and having sockets in their outer faces, gripping washers disposed against the outer faces of the clamping plates upon each post and having 100 projections engaging the sockets in the outer faces of the clamping plates, headed bolts inserted through the said gripping washers and the slots in the clamping plates and through the posts upon which the plates 110 are mounted, springs disposed about the bolts between the heads thereof and the coacting gripping washer, nuts mounted upon the ends of the bolts, and springs coiled about the bolts between said nuts and the coacting 115 gripping washer.

6. In an apparatus for the purpose set forth, the combination of a bench, vertically spaced rods supported above the bench and extending from end to end thereof, posts 120 slidably fitted upon said rods, means carried by the posts to engage said rods and hold the posts in a set position, and box-end-engaging friction clamps carried by each of said posts.

7. In an apparatus for the purpose set forth, the combination of a bench, rests secured upon the bench and extending from front to rear thereof, said rests being provided with transverse grooves and slots 130

opening through the bases of the grooves, and clamping stop plates adjustably supported in the said grooves and provided at their inner opposed ends with upstanding 5 lugs.

8. In an apparatus for the purpose set forth, the combination of end frames, a bench supported by said end frames, bracing bars secured to the end frames and extending from front to rear thereof, means carried by said bars for supporting box-holding members above the bench, extensions carried by the upper bars, standards carried by the rear ends of the extensions, a rail 10 resting on said extensions and against the said standards, and a shelf supported by said extensions between the end frames and the said rail.

9. In an apparatus for the purpose set forth, the combination of end frames, a bench supported by and between the end frames, bracing bars secured upon the end frames and extending from front to rear thereof, upper and lower rods secured to and 20 extending between said bracing bars at the opposite ends of the bench, posts adjustably mounted upon said rods, and box-end-engaging 25 clamps carried by said posts.

10. In an apparatus for the purpose set forth, the combination of corner posts, a bench supported by said posts and adjustable vertically thereon, rods supported by the posts above the bench and extending from end to end of the bench, posts carried 30 by said rods, and box-end-engaging clamps carried by said posts.

11. In an apparatus for the purpose set forth, the combination of end frames, a bench supported by and between said end 40 frames, bracing bars secured to the end frames and extending from front to rear thereof, box-holders supported above the bench by said bracing bars, and a shelf carried by the upper bracing bars at the rear 45 of the end frames.

12. In an apparatus for the purpose set forth, the combination of end frames, a bench supported by and between said end

frames, bracing bars secured to the end frames and extending from front to rear 50 thereof, box-holders supported above the bench by said bracing bars, extensions mounted upon the end frames and projecting rearwardly therefrom, projections on the front ends of said extensions engaging under the upper bracing bars, and a shelf 55 carried by the rear portions of said extensions.

13. In an apparatus for the purpose set forth, the combination of a supporting 60 frame, upright members on the frame, box-end-engaging plates disposed against the sides of the upright members and extending forwardly and rearwardly therefrom, and yieldable means holding the plates to the 65 upright members and permitting limited rocking movement of the plates in horizontal planes whereby the rear ends of the plates may be forced apart to cause the front ends thereof to engage and hold work. 70

14. In an apparatus for the purpose set forth, the combination of a supporting frame, upright members on said frame, box-end-engaging plates disposed against the sides of the upright members and extending 75 forwardly and rearwardly therefrom, and means for holding said plates to the upright members, said means permitting rocking movement of the plates transversely of the upright members and also permitting adjustment of the plates forwardly and rearwardly.

15. In an apparatus for the purpose set forth, the combination of a supporting frame, posts thereon, box-end-engaging 85 plates arranged against the sides of the posts, said plates being provided with longitudinal slots and with sockets in their outer faces, washers fitted against the plates and having projections selectively engaging said 90 sockets, bolts inserted through the washers, the posts, and the slots in the plates, and means carried by the bolts to maintain the washers in engagement with the plates.

In testimony whereof I affix my signature. 95
ERNON V. OLIVER. [L.s.]
